UNITED STATES PATENT OFFICE.

CHESTER McNEIL, OF CHICAGO, ILLINOIS, ASSIGNOR TO UNION SPECIAL MACHINE COMPANY, OF CHICAGO, ILLINOIS, A CORPORATION OF ILLINOIS.

THROAT-PLATE FOR SEWING-MACHINES.

1,264,538.

Specification of Letters Patent. Patented Apr. 30, 1918.

Application filed July 20, 1915. Serial No. 40,888.

To all whom it may concern:

Be it known that I, CHESTER McNEIL, a citizen of the United States, residing at Chicago, in the county of Cook, State of Illinois, have invented certain new and useful Improvements in Throat-Plates for Sewing-Machines, of which the following is a description, reference being had to the accompanying drawing and to the figures of reference marked thereon.

The invention relates to new and useful improvements in throat plates for sewing machines and more particularly to a throat plate adapted to be used in connection with a stitch forming mechanism for forming a flat seam.

The object of the invention is to provide a throat plate having an opening in which the needles of stitch forming mechanisms located one in advance of the other coöperate with a stitch tongue which projects into the opening and across which the looper thread of the front stitch forming mechanism is laid, said stitch tongue having means for supporting said looper thread until after the stitches are formed by the rear stitch forming mechanism.

In the drawings:

Figure 1 is a plan view of a throat plate embodying my improvements;

Fig. 2 is a plan view of the forward end of a work supporting arm having my improved throat plate thereon and also showing the feed dog which coöperates with the throat plate;

Fig. 3 is a view similar to Fig. 2 with the presser foot in place which coöperates with the throat plate;

Fig. 4 is a view partly in vertical section and partly in side elevation showing my improved throat plate, the feed dog, the presser foot, the needles and the looper which coöperates with the needles;

Fig. 5 is a plan view of a throat plate and feed dog having a slightly modified form of the invention;

Fig. 6 is a plan view of the feed dog shown in Fig. 5;

Fig. 7 is a detail showing a portion of the throat plate in plan having a slightly modified form of the invention; and

Fig. 8 is a detail in bottom plan showing more or less diagrammatically the seam formed on my improved throat plate.

I have shown my improved throat plate 1

as secured to the free end of a cylindrical work support 2 by screws 3—3. Said throat plate is provided with spaced parallel openings 4—4, for the outer webs of the feed dog 5. Said throat plate also has openings 6 for the webs 7 of the feed dog. The throat plate, as clearly shown in Figs. 1 and 2 is provided with an opening 8 which is adapted to receive two pairs of needles 9—9 and 10—10. The needles 9—9 are widely spaced 65 while the needles 10—10 are relatively close together.

Coöperating with the needles 9—9 beneath the work support is a looper 11 while a looper 12 coöperates with the needles 10—10. Inasmuch as the needles 10—10 are spaced closer than the needles 9—9 and are directly in rear of the same, the threads of the rear stitching mechanism will be laid on top of the threads of the front stitching mechanism.

In Figs. 3 and 4 of the drawings I have shown a presser foot 13 which is provided with a needle opening 14 for the needles 9—9 and a needle opening 15 for the needles 10—10.

As clearly shown in Figs. 1 and 2 the throat plate is provided with a stitch tongue 16 which may be integral with the throat plate and extends rearwardly into the opening 8. In the center of the throat plate there are openings 17 for the needles 9—9 and slots 18—18 for the threads laid across the stitch tongue and these slots form the side edges of the stitch tongue. It will be noted that the stitch tongue in width is substantially the same as the distance between the needles 9—9. The looper thread of the looper 11 when joining the needles loops of the needles 9—9 will be laid across this stitch tongue. The stitch tongue, as clearly shown in Fig. 2 extends to a point in rear of the needles 10—10 and is formed with a recess 19 for the needles. The looper thread laid across the stitch tongue will, therefore, be held by the stitch tongue until after the stitches are formed across said looper thread by the needles 10—10. This enables the stitches of the rear stitching mechanism to be drawn comparatively tight and at the same time the resulting seam is more or less elastic.

In Figs. 5 and 6 I have shown a slightly modified form of the invention.

The throat plate 1 has spaced parallel 110

openings 4—4 for the outer webs of the feed dog 5. The throat plate is formed with an enlarged opening 20 and the feed dog 5 carries a plate 21 which extends into this opening. This plate 21 carries the stitch tongue 16 which is similar in construction to that above described. Said plate 21 has openings 17—17 for the needles 9—9 and the stitch tongue has a recess 19 for the needles 10—10.

I have shown the stitch tongue in Figs. 5 and 6 as mounted on the feed dog instead of the throat plate as I consider one the full equivalent of the other. The stitch tongue whether mounted on the feed dog or throat plate operates in precisely the same manner as above described. The recess 19 may be, possibly, a little deeper in plate 21 so as to permit the movement of the plate 21 with the feed dog without striking the needles.

In Fig. 7 of the drawings, I have shown a slightly modified form of the invention. In this form, the stitch tongue 16 instead of having a recess in the end thereof, as above described, is formed with an opening 19^a through which the rear pair of needles 10—10 pass. The stitch tongue in this form of the invention operates as above described to support the looper thread of the front stitching mechanism until after the stitches are formed by the rear stitching mechanism.

In Fig. 8 of the drawings, I have shown more or less diagrammatically in bottom plan view a seam formed on my throat plate. In this figure the fabric is indicated at F; the threads of the needles 9—9 are indicated at n—n, while the thread of the looper coöperating with these needles is indicated at l. The threads of the needles 10—10 are indicated at n'—n', while the thread of the looper coöperating with these needles is indicated at l'. It is these looper threads that are laid across the stitch tongue in the manner above described.

It is obvious that minor changes in the details of construction and arrangement of parts may be made without departing from the spirit of the invention, as set forth in the appended claims.

Having thus described my invention what I claim as new and desire to secure by Letters Patent, is:—

1. A throat plate having an opening to receive the needles of stitching mechanisms arranged one in rear of the other, a stitch tongue carried by the throat plate and extending rearwardly into said opening, said stitch tongue having a recess in the rear end

thereof whereby the sides of the stitch tongue project beyond the needles of the rear stitching mechanism.

2. A throat plate having an opening to receive two pairs of needles one in rear of the other, the rear pair of needles being set closer together than the front pair of needles, said throat plate having a stitch tongue extending between the front needles, said stitch tongue having a recess in its rear end, whereby the sides of the stitch tongue extend beyond the rear needles.

3. The combination of a throat plate and a feed dog adapted to coöperate with two pairs of needles one in rear of the other, the rear pair of needles being set closer together than the front needles, one of said elements having a stitch tongue extending between the front needles and formed with a recess at its rear end to receive the rear needles.

4. A plate having an opening to receive the needles of stitch forming mechanism, said needles being arranged in pairs one in rear of the other, the rear pair of needles being closer spaced than the front pair of needles, said plate having a stitch tongue which extends rearwardly into said opening, said stitch tongue being formed with a passage therethrough for the rear pair of needles, whereby said stitch tongue extends on opposite sides of said rear pair of needles to a point in rear thereof for supporting the looper thread of the front looper until the needle loops of the rear pair of needles are laid across the same.

5. A throat plate having an opening to receive the needles of stitch forming mechanisms arranged one in rear of the other, each of said stitch forming mechanisms including spaced needles and a coöperating looper, the needles of the rear stitch forming mechanism being closer spaced than the front pair of needles, said throat plate having a stitch tongue which projects rearwardly into said opening across which the looper thread of the front stitching mechanism is placed, said stitch tongue having a passage for the rear pair of needles whereby the looper thread of the front pair of needles is supported until after the same has passed the rear pair of needles.

In testimony whereof, I affix my signature in the presence of two witnesses.

CHESTER McNEIL.
